DIP BASKET FOR CHEMICALLY TREATING OBJECTS

Victor C. Wallestad, Edina, Minn., assignor to Fluoro-
ware, Inc., Chaska, Minn., a corporation of Minnesota

Filed Apr. 22, 1968, Ser. No. 11,561

Term of patent 14 years

(Cl. D16—1)

FIGURE 1 is a view in perspective of a dip basket for chemically treating objects showing my new design;

FIGURE 2 is a view in side elevation;

FIGURE 3 is a view in top plan thereof;

FIGURE 4 is a view in bottom plan thereof; and

FIGURE 5 is a view in section as seen from the line 5—5 of FIGURE 3.

The dominant features of my invention reside in the portion shown in full line, the handle being fragmentarily shown in FIGURES 1, 2 and 5 for convenience of illustration.

I claim:

The ornamental design for a dip basket for chemically treating objects, as shown and described.
